UNITED STATES PATENT OFFICE.

FRANCIS MORTON CLARK, OF GARDEN CITY, NEW YORK, ASSIGNOR TO MULTIPLE-GRATE-BAR ENDLESS CHAIN STOKER COMPANY, A CORPORATION OF NEW YORK.

MECHANICAL STOKER.

1,120,445.

Specification of Letters Patent.

Patented Dec. 8, 1914.

Application filed November 7, 1911. Serial No. 658,940.

To all whom it may concern:

Be it known that I, FRANCIS MORTON CLARK, a citizen of the United States, residing at Garden City, in the county of 5 Nassau and State of New York, have invented a certain new and useful Improvement in Mechanical Stokers, of which the following is a full, clear, and exact description.

10 My invention is an improvement in mechanical stokers of the endless traveling grate type and relates more particularly to the means for supporting the traveling grate.

15 The object of my invention is to provide a structure by which the frame may, in a large measure, be relieved of the weight of the grate, thus permitting of the frame and shafting being of light material and also 20 doing away with the danger of collapse of the heated frame when the stoker is used under large boilers, where the weight of the grate is very great. To accomplish this result I provide a structure which carries the 25 weight of a large portion of both the upper and lower runs of the grate to the floor independently of the frame.

In the drawings, Figure 1 is a vertical section of the rear of a furnace taken on the 30 line α — α Fig. 2 and looking in the direction of the arrow; Fig. 2 is a partial section on the line y — y , Fig. 1, only a portion of the grate being indicated and the view broken away at the right for lack of space; Fig. 3 35 is a perspective of the U-shaped socket bearing in which the idler and roller shafts are journaled; and Fig. 4 is a diagrammatic view of a modified form of my invention.

As shown in Fig. 1, 5 indicates a boiler and 40 6 an endless traveling grate located in the furnace below said boiler. The grate is composed of grate bars 7 mounted on chains 8 running over sprockets 9 carried on shafts 10 journaled in the ends of a frame of 45 horizontal members 11, 12 joined by vertical members 13. At the rear of the furnace is the usual retarding plate 14 and ash chamber 15 of which only the front wall 16 is shown in the drawings.

50 The structure as so far described is the customary one. The weight of the grate requires that it be supported at various points between the sprocket wheels—the upper run by grooved idlers 17 and the lower run by 55 rollers 18. It has been the practice to

mount the grooved idlers 17 and the rollers 18 on shafts journaled and supported on the frame, but according to my invention, the weight transmitted to the idlers 17 and the rollers 18 is partially or wholly supported 60 independently of the frame. The idlers 17, mounted on shafts 19, are of a diameter equal to the distance between the upper and lower runs of the grate, and roll upon the lower run of the grate. The rollers 18 have 65 bushings 20 set in their ends and these bushings carry short shafts 21. The shafts 19 and 21 are journaled in U-shaped bearings 22 secured to the standards 13. These bearings 22 are so located on the standards 70 that the shafts 19 and 21 normally are at or near the bottoms of the U, which arrangement permits of vertical movement of the shafts but prevents horizontal displacement 75 thereof.

The rollers 18 are shown as resting in roller-bearings 23, 23 carried in standards 24. I have illustrated two such standards for each roller and prefer to employ that number, but it is obvious that one or more 80 than two may be substituted for the number shown without in any way departing from my invention.

In the preferred adjustment of this device the shafts 19 and 21 would, if without 85 any load, be supported by the bearings 22. The load of the grate however will, the shafts being comparatively light, tend to distort the shafts and, as the idlers 17 and the rollers 18 both receive support from below, this tendency to distortion is counteracted and the greater portion of the load is transmitted through the standards 24 to the floor independently of the frame.

On account of irregularities in thickness 95 of the grate it may frequently happen that the shaft 19 will not be home in the lower part of the bearing 22 and so no load at all will be transmitted through the shaft 19 to the frame.

I may, if I desire, so locate the bearings 22 that no load will be transmitted to the frame at any time by the shafts 19, or by either the shafts 19 or the shafts 21, the weight of the upper run of the grate thus 105 being transmitted through the idlers 17 to the lower run of the grate and the combined weight of the upper and lower runs being transmitted through the rollers 18 to the standards 24.

In Fig. 4 I have illustrated a modified form of my invention in which, instead of a number of standards 24 located at different points in the furnace from front to rear, I provide a single standard 25 extending from front to rear and carrying the several sets of roller bearings 23, 23.

Having thus described my invention, what I claim is:

- 10 1. In a mechanical stoker, the combination with an endless traveling grate, of front and rear sprockets over which said grate travels, an idler intermediate said sprockets supported in whole or in part on the lower run of said grate and supporting the upper run thereof, a shaft upon which said idler is mounted, bearings guiding said shaft but permitting of vertical movement thereof, a roller below and supporting the lower run 20 of said grate, bearings guiding said roller but permitting vertical movement thereof, a standard, and roller bearings interposed between said standard and said roller.
- 25 2. In a mechanical stoker, the combination with an endless traveling grate, of front and rear sprockets over which said grate travels, means intermediate said sprockets supported in whole or in part upon the lower run of said grate and supporting the upper 30 run of said grate.
- 30 3. In a mechanical stoker, the combination with an endless traveling grate, of front

and rear sprockets over which said grate travels, an idler supported in whole or in part upon the lower run of said grate and supporting the upper run of said grate, said idler being free to move vertically.

4. In a mechanical stoker, a frame, sprockets mounted at the front and rear of said frame, an endless grate mounted to travel over said sprockets, means intermediate said sprockets supported in whole or in part on the lower run of said grate and supporting the upper run of said grate, and means, independent of the frame, for supporting the lower run of said grate.

5. In a mechanical stoker, the combination with an endless traveling grate, of front and rear sprockets over which said grate travels, an idler intermediate said sprockets interposed and extending between the upper and lower runs of said grate, said idler being supported in whole or in part on the lower run of the grate and so mounted as to be free to move vertically, a roller supporting the lower run of said grate and means independent of the frame for supporting said roller.

In testimony whereof, I hereunto affix my signature in the presence of two witnesses.

FRANCIS MORTON CLARK.
